UNITED STATES PATENT OFFICE.

WILLIAM H. SMITH, OF CLEVELAND, OHIO, ASSIGNOR OF ONE-HALF TO MICHAEL F. BARRETT, OF EAST CLEVELAND, OHIO.

VALVE DEVICE FOR CORROSIVE LIQUIDS.

941,351.

Specification of Letters Patent. Patented Nov. 23, 1909.

Application filed March 5, 1908. Serial No. 481,451.

To all whom it may concern:

Be it known that I, WILLIAM H. SMITH, a citizen of the United States of America, residing at Cleveland, in the county of Cuyahoga and State of Ohio, have invented certain new and useful Improvements in Valve Devices for Corrosive Liquids; and I hereby declare the following to be a full, clear, and exact description of the invention, such 10 as will enable others skilled in the art to which it pertains to make and use the same.

This invention relates to improvements in valve-devices for use with corrosive liquids, and pertains more especially therefore to 15 valve-devices in which every surface which is liable to come in contact with or be exposed to the corrosive liquid conducted through the valve-casing of the valve-device is composed of non-corrodible metal.

One object of this invention is to efficiently but inexpensively reinforce the valve-seat of a valve-casing embodying my invention and having its body composed substantially of comparatively soft and non-corrodible metal.

Another object is to have the valve-seat arranged diagonally of the passageway which is formed in and extends through the body of the valve-casing and employed in 30 conducting a corrosive liquid through the said body, and to have the valve and its stem and the neck of the valve-casing which surrounds the said stem arranged substantially in line endwise to the valve-seat but at an angle to the said body, and not only to reinforce the valve-seat by a hard metal ring or "frame" "cast in" the valve-seat-forming portion of the said body and surrounding the valve-seat but to reinforce the neck by a 35 hard metal bar which is "cast in" the non-corrodible metal of the neck and arranged longitudinally of the longer portion of the neck and formed integral or rigid with the valve-seat-reinforcing hard metal frame and 40 wholly unexposed to the corrosive liquid which may be conducted through the aforesaid passageway.

Another object is to provide the valve-stem-surrounding neck of the valve-casing 50 with a cap which has its body-portion formed by a hard metal section covered at its inner side by a facing of comparatively soft and non-corrodible metal which is cast onto and rigidly held to the said hard metal body-portion.

Another object is to provide the hard metal body-portion of the cap with a bore which is arranged to accommodate the extension of the valve-stem through the cap and has its outer portion enlarged diametrically and the surrounding wall of its said enlarged portion provided with an annular recess, and to have the walls of the said bore, including the walls of the said recess, lined with comparatively soft and non-corrodible metal cast onto and efficiently held to the hard metal body-portion of the cap, and to have the non-corrodible lining of the walls of the said enlarged portion of the said bore forming a chamber for receiving 60 packing applied to form a fluid-tight joint around the valve-stem.

Another object is to provide improved means for establishing operative connection between the valve-stem and the screw employed in shifting the valve-stem and connected valve endwise to open and close the valve as the case may be.

With these objects in view, and to the end of realizing any other advantages hereinafter appearing, this invention consists in certain features of construction, and combinations of parts hereinafter described, pointed out in the claims, and illustrated in the accompanying drawings.

In the said drawings, Figure 1 is a side elevation, largely in central section, of a valve-device embodying my invention. Fig. 2 is a transverse section on line 2—2, Fig. 1, looking in the direction indicated by the arrow. Fig. 3 is a section on line 3—3, Fig. 1, looking in the direction indicated by the arrow. Fig. 4 is a section on line 4—4, Fig. 1. Fig. 5 is a section in detail on line 5—5, Fig. 1, looking in the direction indicated by the arrow.

Referring to the drawings, A indicates the cast-metal body of a valve-casing, which body is composed of comparatively soft and non-corrodible metal, such, for instance, as 100 a composition of lead and antimony, which is not corrodible by the coming in contact therewith of a corrosive liquid conducted through the valve-casing by the passageway 10 which is formed in and extends through the valve-casing and has its ends arranged in line. Internally of the body A of the valve-casing, intermediately between the ends of the passageway 10, is arranged a flaring, circular valve-seat 13 which is there- 105 110

fore composed of non-corrodible metal. The valve-seat 13 is arranged diagonally of the passageway 10 and forms a portion of the surrounding wall of the said passageway. Preferably the valve-seat 13 has such arrangement relative to the ends of the passageway 10 that the valve-seat is nearer the fluid-receiving end 11 than the fluid-discharging end 12 of the passageway and flares in the direction of the last-mentioned end of the said passageway.

The valve-seat 13 is adapted to be engaged by the correspondingly arranged circular endwise movable valve B of my improved valve-device, and obviously continuity in the passageway 10 is interrupted or established according as the valve is in its closed or open position. The valve B has its circumferentially extending edge or surface beveled and is arranged to seat at its said edge against the valve-seat 13 when the valve is closed. The valve B is provided centrally of its rear and diametrically larger end with a stem b which extends externally of the valve-casing in the direction in which the valve-seat flares and consequently leans toward the discharging end of the passageway 10. The valve-stem b extends centrally through a tubular neck 15 with which the body A of the valve-casing is provided. The neck 15 is integral and therefore rigid with the body A and arranged at an angle to the body and tips toward the discharging end 12 of the passageway 10. The valve-seat 13 is arranged therefore substantially in line endwise with the outer end of the neck 15 and the said neck and the valve and its stem are substantially parallel.

All the surfaces of the body A of the valve-casing and its neck 15 which are liable to come in contact with or be exposed to a corrosive liquid conducted by or passing through the passageway 10 in the said body are formed, as already indicated, by a comparatively soft and non-corrodible metal, such, for instance as a composition of lead and antimony, but the valve-seat-forming portion of the body A, to enable it to withstand the pressure against the valve-seat 13 by the valve B in closing the latter, is reinforced, interiorly by a frame D of hard metal such, for instance, as bronze or cast iron. The hard metal frame D is preferably in the form of a ring "cast in" the non-corrodible metal of the valve-seat-forming portion of the body A of the valve-casing during the casting of the said body. The ring D surrounds the valve-seat 13 but is wholly unexposed to the passageway 10. As already indicated, the valve-seat 13 flares in the direction in which the neck 15 projects from the body of the valve-casing, and the ring D preferably has a correspondingly flaring internal surface 14 which is substantially parallel with and arranged in suitable

proximity and concentric relative to the flaring valve-seat 13 and has such arrangement relative to the said valve-seat that the ring at the diametrically smaller end of its internal surface is as small as or smaller 70 diametrically than the diametrically larger end of the valve-seat so as to very efficiently strengthen the valve-seat. By the hereinbefore described form and arrangement of hard metal reinforcement for the non-corrodible valve-seat there is no liability of displacement of the valve-seat in any direction and the valve-seat is kept concentric relative to the line of valve-movement.

The neck 15, leaning toward the discharging end of the passageway 10, obviously has that side of it which faces toward the said end of the said passageway considerably shorter than the opposite side of the neck, and the neck at its last-mentioned and longer 85 side is reinforced interiorly by a bar d of hard metal, such, for instance as bronze or cast iron, which is "cast in" the comparatively soft and non-corrodible metal of the neck during the casting of the body A of 90 the valve-casing. The bar d is wholly unexposed to the passageway 10 or to any corrosive liquid which may be conducted through the valve-casing. The bar d is arranged longitudinally of and substantially 95 parallel with the neck 15. Preferably the bar d is formed integral and consequently rigid with the hard metal ring or frame D. The bar d is preferably curved in cross section concentrically relative to the line of 100 valve-movement as shown in Fig. 5, and provided at its upper end with a flange or member 7 which projects laterally and outwardly into a flange 16 which is formed on and extends circumferentially of the outer 105 end of the neck 15.

By the construction hereinbefore described it will be observed that the bar d and the connected ring D form a simple but strong and efficient reinforcing structure.

The valve-stem b preferably consists of a hard metal rod 17 which is enveloped by soft and non-corrodible metal forming the external surfaces of the valve B and its said stem during the casting of them, and the 110 said rod is enlarged at its inner end centrally of the valve.

Means for hermetically closing the neck 15 at its outer end around the valve-stem b are provided and comprise the non-corrodible soft metal facing g of a cap which overlaps the flange 16 of the neck 15 and has its body-portion G composed of hard metal. That is, the facing g is composed of soft and non-corrodible metal, such, for instance, as 115 a composition of hard metal, such, for instance, as cast iron. The non-corrodible facing g is cast on the body portion G during the casting of the cap. Suitably applied bolts m and nuts n (see Fig. 3) secure the 120 125 130

said cap to the flange 16. The valve-stem *b* extends through and a suitable distance beyond the outer side of the said cap, and the body-portion *G* of the cap is provided centrally with a bore 18 extending therethrough around the valve-stem, and the facing *g* of the cap closes the neck 15 around the said bore. The said body-portion is provided in its inner side with several recesses 19 having undercut side walls and occupied by correspondingly shaped members 21 formed on and projecting from the inner side of the facing *g* which is therefore efficiently held in place.

The bore 18 is enlarged diametrically, as at 25, preferably from a point a short distance from the inner side of the body-portion *G* of the cap to the outer side of the said body-portion, and the surrounding wall of the diametrically enlarged outer portion 25 of the said bore is provided with an annular recess 26. The walls of the bore 18, including the walls of the recess 26, are covered with a lining 27 of soft and non-corrodible metal, such, for instance, as a composition of lead and antimony, which lining is cast onto the said walls and, by its extension into the said recess, is efficiently held in place. The non-corrodible lining of the walls of the enlarged portion 25 of the bore 18 forms a packing-receiving chamber 28 occupied by packing *e* which is compressed by a suitably applied gland *f* to cause the packing to form a fluid-tight joint around the valve-stem, which gland surrounds the valve-stem.

The hard metal body-portion *G* of the cap is provided (see Fig. 3) with a plurality of studs 20 which are arranged parallel with the valve-stem *b*. The studs 20 project loosely through holes in laterally projecting flanges 22 formed on the gland *f* at the outer end of the gland, and nuts *h* are mounted on the studs at the said end of the gland and hold the gland in the desired adjustment. The body portion *G* of the cap is provided at its outer side with a bail-shaped yoke *L* which is formed integral with the said body-portion. The end portions of members 29 and 29 of the yoke *L* are arranged at opposite sides respectively of and spaced equidistantly from the valve-stem, and each yoke-member 29 is provided at its inner side with two laterally spaced parallel flanges 30 which are arranged longitudinally of the said yoke-member.

A screw *R* is arranged at the outer end of and in line endwise with the valve-stem *b* and engages and extends through a correspondingly arranged and correspondingly screw-threaded hole 32 formed in and centrally of the central portion or member 31 of the yoke *L*. The central portion 31 of the yoke therefore forms a nut which is arranged a suitable distance outwardly from the aforesaid cap and engaged

by the screw *R* which is provided at its outer end and a suitable distance from the yoke with a hand-wheel 33 for turning the screw. The screw *R* is operatively connected with the valve-stem *b* in such a manner that the screw can be turned without turning the valve-stem, but the valve-stem and connected valve are shifted endwise by turning the screw, and the valve is actuated to open or close according as the screw is turned in the one or the other direction. The screw *R* is provided at its inner end and externally with an annular recess *r* and the valve-stem *b* is provided at its outer end and externally with an annular recess 35, and my improved operative connection between the valve-stem and the said screw comprises a coupling composed of two sections *T* and *U* which loosely embrace opposite sides respectively of the adjacent ends of the said screw and valve-stem. The coupling-section *T* is provided with two flanges *t* and 36 which engage the recesses *r* and 35 respectively. The coupling-section *U* is provided with two flanges *u* and 37 which engage the recesses *r* and 35 respectively. The coupling-section *T* is provided with a guide-arm 38 which projects between the flanges 30 of one of the end members 29 of the yoke, and the coupling-section *U* is provided with a guide-arm 39 which projects between the flanges 30 of the other of the said end members of the yoke. The guide-arm 38 of the coupling-section *T* is removably secured by a suitably applied screw *x* to an arm or member 40 of the coupling-section *U*, and the guide-arm 39 of the coupling-section *U* is removably secured by a suitably applied screw *y* to an arm or member 41 of the coupling-section *T*. Obviously by this construction the coupling can not turn with the screw. The guide-arms 38 and 39 are sufficiently loose relative to flanges 30 of the yoke to readily permit the removal of the coupling-sections *T* and *U* from the valve-stem and the screw *R* upon detaching the said coupling-sections from each other by withdrawing the screws *x* and *y*.

What I claim is:—

1. In a valve-device for corrosive liquids, a valve-casing having a non-corrodible cast-metal body which is provided interiorly with a passageway extending through the valve-casing and has an annular flaring valve-seat forming a portion of the surrounding wall of the said passageway, said valve-seat being reinforced by a hard metal frame which is in the form of a ring cast in the non-corrodible metal of the valve-seat-forming portion of the body and wholly unexposed to the said passageway, which ring surrounds the valve-seat and has an internal surface which flares in the direction in which the valve-seat flares, said ring at the diametrically smaller end of its said internal

surfaces being as small diametrically as the diametrically larger end of the flaring valve-seat, and a suitably supported endwise movable valve controlling continuity in the said 5 passageway and arranged and beveled to render it capable of seating against the flaring valve-seat.

2. In a valve-device for corrosive liquids, a valve-casing having a non-corrodible cast metal body which is provided interiorly with a passageway extending through the valve-casing and has an annular flaring valve-seat forming a portion of the surrounding wall of the said passageway, said 10 valve-seat being reinforced by a hard metal frame which is in the form of a ring cast in the non-corrodible metal of the valve-seat-forming portion of the body and wholly unexposed to the said passageway, which ring 15 has a flaring internal surface substantially parallel with and arranged in suitable proximity and concentric relative to and surrounding the valve-seat, and a suitably supported endwise movable valve controlling 20 continuity in the said passageway and arranged and beveled to render it capable of seating against the flaring valve-seat, and the aforesaid ring at the diametrically smaller end of its internal surface being as 25 small diametrically as the diametrically larger end of the flaring valve-seat.

3. In a valve-device for corrosive liquids, a valve-casing having a non-corrodible cast metal body which is provided interiorly with a passageway extending through the body and has an outwardly projecting tubular neck, said body having a valve-seat which 30 faces in the direction in which the neck projects from the said body and surrounds the said passageway; a valve controlling the said passageway and arranged to seat against the valve-seat, said valve having a stem arranged centrally of and extending through and a suitable distance beyond the outer end of the neck, and a suitably applied cap arranged to close the outer end of the neck and provided with means for forming a fluid-tight joint around the valve-stem, said cap having a hard metal body-portion which is provided in its inner and neck-facing side with recesses which have undercut walls and are occupied by correspondingly shaped members formed on and projecting from the inner side of a non-corrodible metal facing which forms the inner side of the cap.

4. In a valve-device for corrosive liquids, a valve-casing having a non-corrodible cast metal body which is provided interiorly with a passageway extending through the body and has an outwardly projecting tubular neck, said body having a valve-seat which faces in the direction in which the neck projects from the body; a valve controlling the said passageway and arranged

to seat against the valve-seat, said valve having a stem arranged centrally of and extending through and a suitable distance beyond the outer end of the neck, and a suitably applied cap arranged to close the outer end of the neck around the valve-stem and having a hard metal body-portion which is faced at its inner side with non-corrodible metal and provided centrally with a bore for the valve-stem, said bore having its outer portion enlarged diametrically and having the surrounding wall of its said enlarged portion provided with an annular recess; a non-corrodible metal lining cast onto the walls of the said bore including the walls of the said recess; and the non-corrodible lining of the walls of the said enlarged portion of the bore forming the walls of a packing-receiving chamber; packing within the said chamber, and means for compressing the packing to form a fluid-tight joint around the valve-stem.

5. In a valve-device for corrosive liquids, a valve-casing having a non-corrodible body which is provided interiorly with a passage-way extending through the body and has an outwardly projecting tubular neck, said body having a valve-seat which faces in the direction in which the neck projects from the body; an endwise movable valve controlling the said passage-way and arranged to seat against the valve-seat, said valve having a stem arranged centrally of and extending through and beyond the outer end of the neck and provided at its outer end and externally with an annular recess; a cap arranged to close the outer end of the neck and having means for forming a fluid-tight joint around the valve-stem, said cap being provided at its outer side with a yoke which is rigid with the cap, said yoke having end members arranged at opposite sides respectively of and substantially parallel with the valve-stem and a central member arranged a suitable distance outwardly from the cap and provided with a screw-threaded hole extending therethrough and arranged in line endwise with the valve-stem; a correspondingly threaded screw engaging and extending through the said hole and provided at its inner end and externally with an annular recess; a coupling having members engaging the recesses in the screw and valve-stem and thereby establishing operative connection between the valve-stem and the screw, and means for preventing turning of the coupling with the screw.

6. In a valve for corrosive liquids, a valve-casing having a non-corrodible body which is provided interiorly with a passageway extending through the body and has an outwardly projecting tubular neck and a valve-seat which faces in the direction in which the neck projects from the body; an endwise movable valve controlling the said

passageway and arranged to seat against the valve-seat and having a stem which extends through and beyond the outer end of the neck and is provided at its outer end and 5 externally with an annular recess; a cap arranged to close the outer end of the neck and having means forming a fluid-tight joint around the valve-stem, said cap being provided at its outer side with a bail-shaped 10 yoke which has its end portions arranged at opposite sides respectively of and substantially parallel with the valve-stem and each of the said end portions provided at its inner side with two laterally spaced flanges 15 arranged longitudinally thereof, said yoke having its central portion provided with a screw-threaded hole extending therethrough and arranged in line endwise with the valve-stem; a correspondingly threaded 20 screw engaging and extending through the said hole and provided at its inner end and externally with an annular recess; a coupling establishing operative connection be-

tween the screw and the valve-stem and comprising two sections embracing opposite sides 25 respectively of adjacent portions of the valve-stem and screw and having flanges engaging the recesses in the screw and valve- stem, each coupling-section having two laterally and outwardly projecting arms arranged at opposite sides respectively of the coupling, adjacent arms of the said coupling- sections being removably secured together, and one of the coupling-sections having one 30 of its arms extending between the flanges 35 on one of the end members of the yoke and the other of the said coupling-sections having one of its arms extending between the flanges of the other end member of the yoke.

In testimony whereof, I sign the foregoing 40 specification, in the presence of two witnesses.

WILLIAM H. SMITH.
